UNITED STATES PATENT OFFICE.

ANTON NOSAN, OF CLEVELAND, OHIO.

ADJUSTABLE WING STRUCTURE FOR AEROPLANES.

Application filed August 12, 1926. Serial No. 128,804.

This invention relates to an adjustable wing structure for aeroplanes, and has for its object to provide an aeroplane with wings which can be swung up to an inclined position when a pilot has lost control of the car, so that the wings will have a parachute effect and serve to direct the aeroplane to the ground top side up, without danger of crashing. The wings are normally retained in ordinary position by means of suitable guy ropes controlled by a let off mechanism which when released will allow the wings to swing upwardly so that the aeroplane will flutter down without upsetting.

The invention will be understood from the following description and the accompanying drawings, in which Fig. 1 is a side view of an aeroplane provided with the invention. Fig. 2 is a front elevation. Fig. 3 is a bottom plan view, looking upward. Figs. 4, 5 and 6 are enlarged details of a winding mechanism controlling the guy ropes connected to the wings.

In the drawings, the fuselage is indicated, somewhat diagrammatically, at 5, and having sides 6. A frame 7 is built on the top of the fuselage and has top wings 8 hinged thereto as at 9, at the inner edges of the wings. Lower wings 10 are hinged at 11 to the sides 6 of the fuselage, and these wings have front sections 14 hinged thereto as at 12 and rear sections hinged thereto as at 13, the lines of the hinges being oblique or divergent so that when the sections 14 and 16 swing upwardly they will diverge from the adjacent sides of the fuselage.

The upper and lower wings 8 and 10 are braced by connecting struts 18 hinged to the wings as at 19, and the upper wings 8 and the front and rear wing sections 14 and 16 are connected by guy wires 20 and 21, respectively. By means of this construction, when the lower wings are swung up or down, the upper wings are swung up or down accordingly.

A shaft 22 is journaled in the spaced frames 23 mounted on the bottom 24 of the fuselage. The supports have guide pulleys 25 mounted therein and spaced on the opposite sides of the shaft bearings. Guy ropes 26 are attached to the under side of wings 10 near the outer edges thereof and lead over the pulleys 25 to the winding shaft 22, to which they are secured. Guy ropes 27 are secured to the under sides of the sections 14 and guy ropes 28 are secured to the

under sides of the sections 16, and these ropes also lead over pulleys 25 and are secured to the winding shaft 22.

The shaft 22 has a ratchet wheel 29 thereon, engaged by the teeth of the sliding pawls 31 and 32 pivoted at 33 and 34 to the toggle plates 35. The teeth of the bars 31 and 32 are held in engagement with the teeth of the ratchet wheel by a tension spring 30. A hand lever 36 is pivoted as at 37 to the plates 35 and is fulcrumed as at 38 on brackets secured to the floor 24 of the fuselage, the lever extending thru a slot in said floor in position to be operated by a man in the fuselage.

In operation, the wings 8, 10, 14 and 16 are held in normal flying position as indicated in Figs. 1 and 2 by the guy ropes 26, 27 and 28 which are wound in tension on the winding shaft 22, the rotation of which is prevented by the ratchet bars engaging with the ratchet. The wings are released to the adjusted or inclined position shown in dotted lines in Figs. 1 and 2 by throwing the lever 36 to full forward position, as shown in Fig. 5, until the teeth of the rack bars 31 and 32 are disengaged from the ratchet. This releases the shaft 22 and allows the wings to swing up in consequence of the air pressure incident to drop of the car, the wings 8 swinging up to inclined position on hinges 9, the wings 10 swinging up on hinges 11, and the wings 14 and 16 swinging up on hinges 12 and 13, until the cables are unwound, and this inclination of the wings will cause the aeroplane to drop or flutter down right side up. Springs 40 may be attached between the wings 10 and the fuselage sides to assist in drawing the wings up. To return the wings to normal flying position, the lever 36 is rocked back and forth with the rack teeth of the bars 31 and 32 engaging the ratchet, thereby turning the shaft 22 and winding up the guy ropes and so drawing down the wings to normal position. The toggle arrangement holds one or the other of the rack bars in engagement with the ratchet at all times except at full release as shown in Fig. 5, thereby locking the wheel and preventing the shaft from unwinding.

The full wound position of the parts is shown in Fig. 4 with the guy cables wound in tension on ratchet drums 22 holding the aeroplane wings in normal flying position, the outer teeth of ratchet rack 32 function-

ing as a holding pawl on ratchet 29. A suitable adjustable stop 50 may be provided if desired, for abutment of lever 36 when rocking the lever for winding of the wing cables 5 preventing releasing of the racks.

To release the ratchet wheel, guy cables and wing structure, the racks 31 and 32 are pulled forward by lever 36 as shown in Fig. 5. The aeroplane wing structure has sufficient spring qualities to permit the last teeth of ratchet rack 32 to be pulled clear 10 of the ratchet wheel 29. Suitable guides 51 and 52 are provided for the racks 31 and 32 which are drawn together by spring 30.

To wind the wing cables, the racks are pushed into engagement with the ratchet wheel by lever 36 near the position shown in Fig. 4, the first tooth 54 of rack 31 engaging a tooth of wheel 29, the oppositely 20 arranged teeth of rack 32 riding over the wheel teeth. Upon pushing rack 31 fully back to the position shown in Fig. 6 by means of lever 36 which is pushed forward, the teeth of rack 31 engage the wheel teeth 25 turning the wheel 29 and drum 22 winding the wing cables against the tension of wing springs 40. The teeth of rack 32 when pushed rearwardly ride over the wheel teeth. If the lever 36 is released, a tooth 30 of rack 32 is engaged by spring 30 with a wheel tooth holding the wheel against the engaging teeth of rack 31.

Upon rocking lever 36 rearwardly, the rack 32 is pulled forward to the initial posi-

tion shown in Fig. 4, the teeth thereof now 35 engaging the wheel teeth and turning the wheel 29 and drums 22 winding the wing cables thereon. The teeth of rack 31 now ride over the wheel teeth and act as a stop pawl thereon when the lever is released. 40

The cycle of operation is repeated by rocking the lever 36 forward and backward until the wing cables are wound on drums 22.

Various changes may be made in the details of the device without departing from the scope of the invention.

I claim:

1. An aeroplane provided with upper and lower side wings, the upper wings being 50 hinged to the fuselage, each lower wing comprising a middle section hinged to the side of the aeroplane fuselage and front and rear sections hinged to the front and rear edges of each middle section, struts connecting the 55 upper wings to the middle sections of the lower wings, guy ropes connected to the respective sections, and a winding mechanism carried by the fuselage operable therefrom while the machine is in flight and controlling said guy ropes.

2. An aeroplane as set forth in claim 1, the front and rear sections being connected to the middle sections of the wings on oblique diverging lines. 60 65

In testimony whereof, I do affix my signature.

ANTON NOSAN.
